J. MOSCHOS,
SAFETY DEVICE FOR ELEVATORS,
APPLICATION FILED JULY 29, 1921.

Patented Aug. 1, 1922.

By

John MOSCHOS

Attorney

UNITED STATES PATENT OFFICE.

JOHN MOSCHOS, OF DEMOPOLIS, ALABAMA.

SAFETY DEVICE FOR ELEVATORS.

1,424,665.

Specification of Letters Patent. Patented Aug. 1, 1922.

Application filed July 29, 1921. Serial No. 488,368.

To all whom it may concern:

Be it known that JOHN MOSCHOS, a citizen of the United States of America, residing at Demopolis, in the county of Marengo 5 and State of Alabama, has invented new and useful Improvements in Safety Devices for Elevators, of which the following is a specification.

The object of the invention is to provide 10 safety cushioning means for passenger and other elevators as a means of protecting the occupants of the car in the event of the fall thereof through the breakage or disarrangement of the suspending devices and further- 15 more to provide means for this purpose which can be positioned and permanently occupy a relation with the car or cage adapting them to perform the intended function without in any way interfering with the 20 equipment of the elevator in other respects and without requiring any modification in the construction or operation thereof; and with this object in view the invention consists in a construction and combination of 25 parts of which a preferred embodiment is shown in the accompanying drawings, wherein:—

Figure 1 is an elevation of an elevator equipment provided with a safety appliance 30 embodying the invention.

Figure 2 is a plan view partly broken away of the bottom cushioned platform.

Figure 3 is a detail view of one of the 35 supporting elements of the bottom platform.

Figure 4 is a similar view of one of the upper cushioning elements.

Figure 5 is a detail view of one of the car carrier buffers.

The apparatus consists of a yieldingly 40 supported or cushioned platform 10 at the bottom of the elevator shaft, the angles of the platform being extended through slots 11 in tubular guides 12 which contain coiled cushioning springs 13 held under a moderate 45 tension and adapted when a weight is suddenly applied to the platform as by the fall of the car or cage indicated at 14 to yield and thereby cushion the shock. At the upper ends of the coils 13 are arranged buttons 15 50 from which extend cables 16 passing through guide eyes 17 at the bottom and top of the car or cage and attached at their upper ends

to buttons 18 arranged in operative relation with coiled cushioning springs 19 arranged in tubular guides 20, said guides being permanently secured to the building or frame work so that the springs 19 therein are subjected to strain through the cables 16 when the springs 13 are compressed by the depression of the platform 10. In other words the overhead or upper cushioning devices including the springs 19 serve to reinforce those which are located in supporting relation with the platform 10, to minimize or absorb the shock or jar incident to the falling of the car or cage.

As an additional means of modifying the shock and hence the possibility of injuring the occupants of the car the latter is provided at its bottom with a cushion which as illustrated in the drawing may consist of the bowed frames 21 having coiled filler springs 22 and constituting a buffer for contact with the surface of the platform 10. It will be obvious that the combined effect of the several cushioning devices will be such as to absorb the jar incident to the checking of the movement of the car or cage and bring it to a state of rest with the minimum of shock to the occupants of the car so that the injury to passengers ordinarily resulting from an accident of this character may be practically eliminated.

Having described the invention, what is claimed as new and useful is:—

1. A cushioning device for elevators having a spring supported platform arranged in the path of downward movement of the cage, the platform supporting springs being supplemented by overhead cushioning springs arranged at the upper end of the elevator shaft and connected therewith by cables extended parallel with the path of the cage.

2. A cushioning device for elevators having a spring supported platform arranged in the path of downward movement of the cage, buttons being connected with the upper ends of the platform supporting springs and supplemental reinforcing springs being arranged at the upper end of the elevator shaft and provided with terminal buttons connected with those of the platform supporting springs by cables extending parallel

with the path of movement of the elevator cage.

3. A cushioning device for elevators having a spring-supported platform arranged in the path of downward movement of the cage, buttons being connected with the upper ends of the platform supporting springs and supplemental reinforcing springs being arranged at the upper end of the elevator

shaft and provided with terminal buttons 10 connected with those of the platform supporting springs by cables extending parallel with the path of movement of the elevator cage, the said supplemental springs being arranged in tubular housings. 15

In testimony whereof he affixes his signature.

JOHN MOSCHOS.
